UNITED STATES PATENT OFFICE.

PHILIP A. MYERS, OF ASHLAND, OHIO.

DESIGN FOR A PUMP-FRAME.

SPECIFICATION forming part of Design No. 31,326, dated August 1, 1899.

Application filed June 3, 1899. Serial No. 719,313. Term of patent 14 years.

To all whom it may concern:

Be it known that I, PHILIP A. MYERS, a citizen of the United States, residing at Ashland, Ohio, have invented and produced a new and 5 original Design for Pump-Frames, of which the following is a specification, reference being had to the accompanying drawings, in which—

Figure 1 is a front elevation; Fig. 2, a rear 10 elevation, and Fig. 3 a side elevation.

As shown in the figures, the leading or material feature of the design is in the configuration of the frame. A substantially cylindrical base A terminates in a stepped and 15 flaring flange *a* at its lower end, and at its upper end the base terminates in a cylindrical head B of slightly-increased diameter. Between the base A and the head B is a projection *b*, formed by flanges on each part abutting and

being joined together. The head B has a reduced neck *c*, and from this extends a nozzle *d*. From the sides of the base A angular projections *e* extend at an angle to the line of the base, forming sockets *f*. Surmounting the head B is an open frame C, having a lower 25 flange *g*, forming a connection with the head. The frame C has an upper contracted part and a lower part of greater width.

What I claim is—

The design for a pump-frame herein shown 30 and described.

In testimony whereof I affix my signature in presence of two witnesses.

PHILIP A. MYERS.
